United States Patent

Des. 238,327

Patented Jan. 6, 1976

238,327

FURNITURE BASE OR SIMILAR ARTICLE

Robert F. George, 8 Carol Court, Crugers, N.Y. 10521

Filed June 29, 1973, Ser. No. 375,058

Term of patent 14 years

Int. Cl. D6—06

U.S. Cl. D6—196

FIG. 5

FIG. 4

FIG. 1 is a top plan view of a furniture base or similar article showing my new design;

FIG. 2 is a bottom plan view;

FIG. 3 is a side elevational view;

FIG. 4 is a top plan view of a second embodiment of a furniture base or similar article showing my new design wherein three feet are evenly spaced about a central post; and

FIG. 5 is an elevational view thereof.

I claim:

The ornamental design for a furniture base or similar article, substantially as shown and described.
